UNITED STATES PATENT OFFICE

GUSTAVUS A. PFEIFFER, OF NEW YORK, N. Y.

DUPLEX FACE POWDER BOX

Application filed August 23, 1929. Serial No. 387,827.

This invention relates to containers in general and more especially to face powder boxes.

Among the objects of the present invention it is aimed to provide a container or face powder box having two compartments, one accessible from the top by means of a cover and the other accessible from the side by means of a hinged slide.

It is still another object of the present invention to provide a face powder box which can conveniently house two types of powder separated from one another so that a user can as desired use either one type of powder or the other according to the occasion.

It is well known that today women use different types and shades of face powder according to the occasion, such for instance as a day face powder and a night face powder which may have different characteristics and generally are different in shade. To this end, the present invention aims to provide a container which has two compartments separated from one another, one to contain the day face powder and the other to contain the night face powder.

It is still a further object of the present invention to provide a face powder box having two separate compartments, one a larger compartment to contain a supply of day face powder occupying substantially the upper two-thirds of the entire interior area of the container and another a smaller compartment to contain a supply of night face powder occupying substantially the lower one-third of the entire interior area of the container, and which compartments are opened in distinct manners, the compartment for the day face powder being accessible from the top by means of an ordinary cover and the compartment for the night face powder which is constructed to receive a slide or drawer being accessible by withdrawing the slide from the lower compartment.

These and other features, capabilities and advantages of the invention will appear from the subjoined detail description of one specific embodiment thereof illustrated in the accompanying drawings in which

Figure 1 is a side elevation showing the

slide for the lower compartment in closed position in full lines and in open position in dotted lines;

Fig. 2 is a plan view of the same with the cover removed and again showing the slide in open position in dotted lines;

Fig. 3 is a transverse section on the line 3-3 of Fig. 1; and

Fig. 4 is a longitudinal section on the line 4-4 of Fig. 1 showing the slide in open position.

In the embodiment illustrated, there is provided a container A having a cylindrical wall member 1 preferably composed of two layers of cardboard 2 and 3, to the inner periphery of which, adjacent its lower edge, is provided a base portion or lower box closure member 4. To the inner periphery near its upper edge, the cylindrical wall 1 has secured thereto a second container portion B preferably having a cylindrical wall 5 composed of three layers of cardboard 6, 7 and 8; the central layer of which, 7, in the present instance, continues into and forms the base portion 9 of the container B to form the bottom 70 of the container portion B or upper compartment 75 10.

The cylindrical wall 5, as clearly appears from Fig. 3, is substantially twice the size of the cylindrical wall 1 from the bottom 9 to the bottom 4. The cylindrical wall 5 of the container portion B above the cylindrical wall 1 of the container portion A forms a recess or seat for the cylindrical wall 11 of the cover C having an upper closure portion 12. 85

To the lower compartment 13 formed by the container portion A between the base portions 9 and 4, an opening is formed by removing a portion of the inner layer 2 of the cylindrical wall 1, such opening extending substantially one-half way around the cylindrical wall 1. The outer layer 3 is cut at one end of this opening, to wit at the end 14 and forms a hinge at the other end of this opening, to wit at the end 15. 95

The portion of this layer 3 around this opening so formed, and for convenience designated 3', is provided with an inner layer 3a which is secured to the outer periphery 100 of the cylindrical wall 16 of the slide D. The

cylindrical wall 16 of the slide D, as illustrated, is preferably composed of three layers of cardboard 17, 18 and 19, the layer 19 preferably continuing into and forming the base portion 20 of the slide D.

The layers 3' and 3a secured to the slide D preferably extend above the opening 21 to form an edge flange which will engage the lower edge of the outer layer 8 of the container portion B, and the layer 3' preferably forms an edge flange which extends beyond the edge of the inner layer 2 at the edge 14, and thus forms a flange closure for two sides of the opening 21.

13 The compartment 10 formed by the container portion B is preferably used for a supply of day face powder and the compartment 22 formed by the slide D is preferably used to house a supply of night face powder.

20 In this manner one and the same container can be used to conveniently house the two main face powders today used by the well-dressed woman, as a result of which the dressing table will be burdened with at least

25 one less container, and in turn when traveling the user is again burdened with at least one less container.

On the other hand, by means of this duplex container, the likelihood of spilling is reduced to a minimum in that two entire different modes of action are required to gain access to the two compartments, the cover for the upper compartment being removable with an upward direction and the slide D for the lower compartment being moved laterally at right angles to the movement of the cover C when opening or closing the cover C.

For conveniently gripping the slide D, the same is preferably provided with a button 23 secured to the layer 3' and cylindrical wall 16 adjacent to the inner end 24 of the layer 3'.

The likelihood of spilling powder is further minimized by the proportions of the slide D to the compartment 22, it appearing 45 that the outer periphery of the cylindrical wall 16 of the slide D corresponds in size to the inner periphery of the inner wall of the compartment 22, and that the height of the slide or drawer D is such that its upper edge 50 just clears the lower face of the base 9 of the container 10, as a result of which the slide D fits snugly in the compartment 22 in closed position and there is no space in the compartment 22 into which the powder may spill 55 when the slide D is moved into closed position, the slide D practically displacing all of the area of the compartment 22 when in closed position.

In the present instance, the compartment 60 10 is shown as at least twice the size of the compartment 22 so that the compartment 10 can contain the larger supply, to wit, a supply of day face powder as distinguished from the supply of night face powder to be housed 65 in the compartment 22, it being understood

that ordinarily a great deal more day face powder is used than night face powder.

It will also appear from the foregoing that the cylindrical wall 5 and the cylindrical wall 1 of the container portions B and A respectively form a composite wall for the entire duplex container formed by the container portions B and A respectively. 70

It is obvious that various modifications and changes may be made to the details of construction without departing from the general spirit of the invention as set forth in the appended claims. 75

I claim:

1. In a duplex face powder box, the combination with an inner cylindrical cardboard wall forming the lateral wall of an upper compartment, of a base portion secured to said inner cylindrical wall to form the bottom of said upper compartment, an outer cylindrical cardboard wall secured to said inner cylindrical cardboard wall and extending down below the bottom of said upper compartment, a second base portion secured to the lower end of said outer cylindrical cardboard wall, the outer cylindrical cardboard wall being spaced at its upper edge from the upper edge of said cylindrical cardboard wall to form a cylindrical recess, a cover for the upper compartment, said cover having a cylindrical wall fitting into said cylindrical recess when in closed position, there being an incision formed in the outer cylindrical wall below the base portion of said upper compartment to form an outwardly swinging semi-cylindrical flap, a portion of said flap overlapping said inner cylindrical wall to form a limiting stop therefor, and a cylindrical drawer secured to said flap movable into said lower compartment in closed position, the ends of the incision being spaced apart a distance corresponding to the diameter of the drawer. 90

2. In a face powder box, the combination with an inner cylindrical cardboard wall forming the lateral wall of an upper compartment, of a base portion secured to said inner cylindrical wall to form the bottom of said upper compartment, an outer cylindrical cardboard wall secured to said inner cylindrical wall and extending down below the bottom of said upper compartment, a second base portion secured to the lower end of said outer cylindrical wall, said outer cylindrical wall being composed of two concentric cylindrical layers, the inner layer having a rectangular four-sided incision formed therein, the outer layer having a rectangular three-sided incision to form a tongue integral at one end with said main outer layer to form a hinge, a four-sided strip corresponding to said four-sided incision secured to said tongue to form a flap hinged to said outer layer by said integral hinged portion, a portion of said flap overlapping said inner cylindrical 100

wall to form a limiting stop therefor, and a drawer secured to said flap movable into and out of said lower compartment.

3. In a face powder box, the combination
 5 with an inner cylindrical cardboard wall, of a base portion secured to said wall, an outer cylindrical cardboard wall secured to said inner wall and extending down below the bottom of said base portion, a second base portion secured to the lower end of said outer wall to form a compartment, said outer wall being composed of two concentric cylindrical layers, the inner layer having a rectangular four-sided incision formed therein, the outer 10 layer having a rectangular three-sided incision to form a tongue integral with said main outer layer at one end to form a hinge, a four-sided strip corresponding in size to said four-sided incision secured to said tongue to form a flap hinged in place by said integral hinged portion, a portion of the upper edge of said flap overlapping said inner cylindrical wall in closed position, the end of the inner layer of said outer cylindrical 15 wall adjacent to one end of said incision extending beyond the outer layer to form a recessed shoulder at the end of said incision and the end of the outer layer of the flap adjacent to said latter end of the incision extending beyond the end of the inner layer of the flap to form a recessed shoulder to engage the recessed shoulder at the end of the incision in closed position, and a drawer secured to said flap movable into and out of said compartment.

4. In a face powder box, the combination
 with an inner cylindrical cardboard wall, of a base portion secured to said wall, an outer cylindrical cardboard wall secured to said inner wall and extending down below the bottom of said base portion, a second base portion secured to the lower end of said outer wall to form a compartment, said outer wall being composed of two concentric cylindrical layers, the inner layer having a rectangular four-sided incision formed therein, the outer layer having a rectangular three-sided incision to form a tongue integral with said main outer layer at one end to form a hinge, a four-sided strip corresponding in size to said four-sided incision secured to said tongue to form a flap hinged in place by said integral hinged portion, a portion of the upper edge of said flap overlapping said inner cylindrical wall in closed position, the end of the inner layer of said outer cylindrical wall adjacent to one end of said incision extending beyond the outer layer to form a recessed shoulder at the end of said incision and the end of the outer layer of the flap adjacent to said latter end of the incision extending beyond the end of the inner layer of the flap to form a recessed shoulder to engage the recessed shoulder at the end of the incision in closed position, and the cylindrical

wall of a drawer secured to said flap so that said drawer may slide into and out of said compartment with its base parallel to the bases of said compartment, said cylindrical drawer corresponding in outer periphery to the inner periphery of said outer cylindrical wall to fit snugly in said compartment in closed position.

5. In a face powder box, the combination
 with an upper base, of a lower base, a cylindrical wall secured to the peripheries of said bases to form a cylindrical compartment, said cylindrical wall being composed of two concentric cylindrical layers, the inner layer having a rectangular four-sided incision formed therein, the outer layer having a rectangular three-sided incision formed therein to form a tongue integral with said main outer layer at one end to form a hinge, a four-sided layer corresponding to said four-sided incision secured to said three-sided tongue to form a flap hinged to said outer layer by said integral hinged portion, and the cylindrical wall of a cylindrical drawer secured to said flap so that it may slide into and out of said compartment with its base parallel to the bases of said compartment, the outer cylindrical periphery of said cylindrical drawer corresponding in size to the inner cylindrical periphery of said cylindrical wall and corresponding in altitude to the altitude between the bases of said compartment to snugly fit in said compartment in closed position and thus protect the powder contents of the drawer from being spilled in said compartment.
